UNITED STATES PATENT OFFICE.

CHARLES LEONARD SCHWALM, OF NEW BRITAIN, CONNECTICUT.

CLOTHES-LINE SUPPORT.

SPECIFICATION forming part of Letters Patent No. 592,099, dated October 19, 1897.

Application filed July 6, 1897. Serial No. 643,590. (No model.)

To all whom it may concern:

Be it known that I, CHARLES LEONARD SCHWALM, a citizen of the United States, residing in New Britain, in the county of Hartford and State of Connecticut, have invented 5 certain new and useful Improvements in Clothes-Line Supports, of which the following is a specification.

This invention relates to a clothes-line support primarily intended for use in connection with endless or double clothes-lines, the object being to provide a simple and inexpensive device of this character which in operation serves as a means for equalizing the 10 strain or weight applied by a mass of clothing suspended from the lower run of the line, so that such strain is exerted nearly equally to the upper run thereof, whereby the line will not materially sag or drop at its middle 15 or at any other point intermediate its end supports.

In the drawings accompanying and forming part of this specification, Figure 1 is a side elevation of an endless clothes-line 20 equipped with my support, illustrating the latter in its working position. Fig. 2 is a side elevation of the support with its locker in the ineffective position thereof, a portion of the line being also represented in said figure; and Fig. 3 is a cross-sectional view taken 25 in the line $x-x$, Fig. 1, and as seen from the right, the left-hand support for the line not being illustrated in said figure.

Similar characters designate like parts in 30 all the figures of the drawings.

My improved clothes-line support (designated in a general way by S) embodies a longitudinal body portion bifurcated at its opposite ends, the upper bifurcation being intended to receive a wheel or pulley adapted to 35 travel along the upper run of the line, and the space within the lower bifurcation serving as a pocket to receive a shoe or pad of yielding or elastic material, such as rubber, and a locker consisting of a lever provided with a cam-head preferably recessed or notched and pivoted between the branches of the lower bifurcation, so as to coöperate with the said shoe or pad and to act as a clamp for biting 40 or gripping the lower run of the line to hold the support in a fixed or predetermined position, which is generally at its middle, al-

though it is obvious that in a very long line a plurality of the supports may be employed.

The line is designated by L, it being of the 55 "endless" class and passed around the supporting-pulleys 2 and 3, whose brackets 4 and 5, respectively, can be suitably secured to convenient supports, the house end of the line being designated by H.

The support S comprehends a body portion, such as B, consisting of a longitudinal bar bifurcated at its opposite ends, as at 6 and 7, respectively, said body portion being conveniently made in one piece.

The upper and lower runs 8 and 9, respectively, of the clothes-line pass between the branches of the bifurcations 6 and 7, as shown in Fig. 3, so that the support, in connection with a suitable pulley or wheel mounted 70 between the upper bifurcation and a locker supported between the lower bifurcation, is maintained positively in place on the line. A grooved roller or pulley is shown at 10, it being supported between the members or 75 branches of the upper bifurcation. The pulley has the projecting pivots 12 and 13, respectively, on its opposite faces, working in bearings or apertures in the two branches of 80 the bifurcation, and is located over the upper run of the line. The lower bifurcation 7 is widened out at its upper end, as at 15, to form a pocket 16 for the reception and the retention of a shoe or pad of yielding material, such as rubber, said rubber shoe or pad 85 being designated by 17 and being of a shape corresponding with the shape of its pocket 16 to fit tightly therein.

The locker for the support is designated by 18, and it consists of a lever pivoted between 90 the branches of the lower bifurcation 7. The locking-lever 18 has a cam-head or enlargement 19, provided with oppositely-disposed pivots 20 and 21, respectively working in bearings in the two branches of the lower 95 bifurcation 7, as represented in Fig. 3.

The lower run 9 of the clothes-line L is passed between the branches of the lower bifurcation 7, the yielding pad or shoe 17 lying over and substantially contiguous to or 100 against said lower run. The working face or portion of the cam-head 19 has a recess or notch 22, adapted to partially receive the lower run of the line, so that the rope, on the

release of the cam-lever 18, can be forced tightly against the shoe or pad 17.

The handle portion *h* of the lever is gravitational or self-active, it being weighted, as at 5 *h'*, to a sufficient degree, so that when released it will drop from a substantially horizontal to a vertical position to force the cam-head 19 against the lower run 9 of the line, thereby, in conjunction with the rubber shoe 17, tightly 10 gripping said line.

In Fig. 2 the cam-lever is shown in its ineffective position, where it is held by a suitable detent, such as the spring-catch 25, secured, as at 26, to the widened portion 15 of 15 the body portion B, the hook 27 of said catch being adapted to engage the projection or lug 28 on the handle *h* near the cam-head 19. The spring-catch 25 terminates in a finger-piece 29. To release the weighted handle *h* 20 so that it can drop, the finger-piece 29 is pressed outward and the hook 27 of the catch swung from under the projection 28.

In use the lower run 9 of the line will be filled with clothing to about its middle, and 25 the support S will then be locked or clamped to the line by the release of the lever 18, in the manner aforesaid. The remaining half of the lower run 9 will then be utilized as a support for clothing, the support itself being, 30 when the line is completely filled with clothing, situated at the middle of said line, as represented in Fig. 1, so as substantially to tie two runs of the line at their middle, whereby the strain exerted by the clothing is approximately 35 equally applied to each run, so as to prevent material sagging of the line. When not in use, the support will be stationed at the house end II of the line and the locking or cam lever 18 unclamped from the lower run 40 9, as shown in Fig. 2, and held by the spring-catch 25.

When the clothing is placed on the lower run of the line, the upper run thereof will be

grasped and fed in the direction indicated by the arrow in Fig. 1.

Having described my invention, I claim—

1. A support for endless clothes-lines, consisting of a longitudinal body portion bifurcated at its opposite ends; a wheel pivotally supported between the branches of the upper bifurcation; an elastic shoe fitted in a pocket formed by the lower bifurcation; and a locking-lever pivoted between the branches of the lower bifurcation and having a cam-head adapted to coöperate with said shoe. 45

2. A support for endless clothes-lines, consisting of a longitudinal body portion; a wheel supported at the upper end of the body portion; an elastic shoe fitted in a pocket formed in the lower part of the body portion; a locking-lever pivoted to said body portion and having a weighted handle and also having a cam-head adapted to coöperate with said shoe; and a spring-catch secured to the body portion and furnished with a hook adapted to engage a 65 projection on said handle portion.

3. A support for endless clothes-lines, consisting of a longitudinal body portion bifurcated at its opposite ends and widened near its lower end; a wheel pivotally supported between the branches of the upper bifurcation; an elastic shoe fitted in a pocket formed by the lower bifurcation; a locking-lever provided with a cam-head pivoted between the branches of the lower bifurcation and having a line-receiving notch, the handle of the locking-lever being weighted and furnished with a projection near the cam-head; and a spring-catch secured to said widened portion and having a hook adapted to engage said projection. 75
